UNITED STATES PATENT OFFICE.

BENJAMIN H. JEFFERSON AND WALTER I. KIRK, OF CHICAGO, ILLINOIS, ASSIGNEES,
BY MESNE ASSIGNMENTS, TO LYON & HEALY, INC., OF CHICAGO, ILLINOIS, A
CORPORATION OF ILLINOIS.

PEDAL DEVICE FOR PIANOS AND FOR OTHER PURPOSES.

Application filed May 15, 1919. Serial No. 297,378.

To all whom it may concern:

Be it known that we, BENJAMIN H. JEFFERSON and WALTER I. KIRK, citizens of the United States, residing at Chicago, in the county of Cook and State of Illinois, have invented a certain new and useful Improvement in Pedal Devices for Pianos and for Other Purposes, of which the following is a full, clear, concise, and exact description, reference being had to the accompanying drawings, forming a part of this specification.

Our invention relates to pedal devices, such as are used for pianos and for other purposes.

One of the objects of the invention is to provide a pedal device of the class mentioned which can be acted upon at a point or position above the one which is usually or normally acted or pressed upon.

Another object of the invention is to permit the pedal device to be operated by acting upon it at such usual or normal position, as well as at such elevated point or position.

Another object of the invention is to secure these pressing surfaces at different horizontal levels by means of a construction similar in general shape and character to the usual piano pedal.

Another object of the invention is to arrange for the easy, ready and quick adjustment of such relatively adjustable parts.

Another object of the invention is to secure simplicity and practicability of construction and operation.

Another object of the invention is to accomplish the foregoing and other desirable results in a simple and expeditious manner.

In the accompanying drawings Fig. 1 is a view showing a portion of the front of a piano provided with three pedals, one of which is provided with a device embodying my present invention for permitting its use by acting upon an elevated pressing surface;

Fig. 2 is a vertical section taken on line 2-2 in Fig. 1.

Referring to the drawings we show a portion 1 of the front of a piano, and three pedals 2, 3 and 4, for the same. The pedals 2 and 3 are in condition to be operated in the usual manner. The pedal 4 is in condition to

be operated by a child or short-legged person.

The pedal 4 is mounted on a pedal bar 4^a, which is understood to be connected with suitable mechanism inside the piano. Said pedal 4 is provided with an aperture near its front end, and a pin 5 is inserted into said aperture. Said pin 5 is preferably somewhat tapered at its lower end as at 6, so as to permit it to be readily inserted and withdrawn from the aperture, and also to fit tightly within the same when inserted. Said pin 5 has its upper end provided with a head 7 forming a broad enough surface for the foot of a person using the piano to rest upon and press. Thus when the pin 5 is in position the head 7 will form an elevated pressing surface upon which the foot can act and consequently children or other persons with short legs can play the piano very readily simply by putting the pin 5 in position. When the piano is to be played by a mature person or in the normal or usual way, the pin 5 is withdrawn from the aperture or socket in the pedal 4, and the latter is used in the regular way.

The pedals 2 and 3 are also intended for use in the same way that the pedal 4 is. To such end said pedals 2 and 3 are provided with apertures 2^a and 3^a, respectively, into which pins similar to the pin 5 may be inserted. Such pins are not shown herein as it is intended that when they are not used they will be put aside in some convenient place.

It will be understood that changes and modifications may be made without departing from the spirit of the invention.

What we claim is:

A pedal provided with a pressing surface for the foot and having an aperture in said surface and a pin having its lower end fitted detachably into said aperture and its upper end constructed to provide another pressing surface for the foot.

In witness whereof, we hereunto subscribe our names this 24th day of April A. D., 1919.

BENJAMIN H. JEFFERSON.
WALTER I. KIRK.
